The ornamental design for a jeweled trim for a sandal, as shown and described.

DESCRIPTION

FIG. 1 is an exploded view of a jeweled trim for a sandal according to an embodiment of the invention.

FIG. 2 is a front perspective view thereof, with the strap and ornament connected to the strap;

FIG. 3 is an enlarged view of a portion of the jeweled trim for a sandal, where it is seen that the particular facet pattern of the gems forming the jeweled trim is shown in broken lines.

FIG. 4 is a front view of the ornamental design for a jeweled trim for a sandal of FIG. 2.

FIG. 5 is a rear view of the ornamental design for a jeweled trim for a sandal of FIG. 2.

FIG. 6 is a right-side view of the ornamental design for a jeweled trim for a sandal of FIG. 2.

FIG. 7 is a left-side view of the ornamental design for a jeweled trim for a sandal of FIG. 2; and,

FIG. 8 is a top view of the ornamental design for a jeweled trim for a sandal of FIG. 2.

The structures depicted in broken lines in the figures are environmental structures and forms no part of the claimed design. For clarity, FIGS. 1 and 4-8 are shown with the central jewel and decorative straps removed. The region between the upper and lower jeweled straps is not part of the claim.
